MARTIN P. LUTHER

E. Kennedy Atty.

UNITED STATES PATENT OFFICE.

MARTIN P. LUTHER, OF CHICAGO, ILLINOIS, ASSIGNOR TO SUPER SAFETY SWITCH CO., OF CHICAGO, ILLINOIS, A CORPORATION OF ILLINOIS.

ELECTRIC SWITCH.

Application filed March 21, 1927. Serial No. 177,137.

My invention relates to electric switches, and has more particular reference to a multiple or "gang" switch, and the manner of arranging and operating the principal elements 5 thereof.

It is one of the objects of my invention to provide a switch wherein the parts are arranged in a box so that the fuses are positioned to be conveniently and readily handled 10 for removal and replacement, and in which the live portions of the structure are positioned so that they would not injure an ordinary careful person working about the box. Another object resides in the arrangement 15 or disposition of the operating elements of the switch upon the sides of the box in as flat a position as possible so as to leave the bottom and central portions of the box clear of such parts for the installation of the conductors or cables which latter, in high-powered circuits, are of large proportions and cumbersome to handle and install. The arrangement such as I have herein disclosed permits of no interference by the fuses, and the circuits 20 are cut in and out by means of double operating switch elements one pair arranged upon each side of the box and movable simultaneously to make or break a single circuit or when several are arranged in gang formation 25 to control a corresponding number of circuits. In this connection the fuse or fuses will bridge the space between opposite pairs of switch elements of each circuit.

Other objects and advantages of my present structure will be apparent as the description proceeds, and it is proposed to accomplish the several objects and to carry out my invention in substantially the manner hereinafter fully described and as more particularly pointed out in the claims. I now refer to the accompanying drawings for a more complete understanding of my invention, which drawings form a part of this specification.

45 In the drawings:—

Figure 1, is a view looking into the switch-box with the door or cover opened and the parts of the switch drawn in plan.

Figure 2 is a longitudinal section taken on 50 line 2—2 of Figure 1, looking in the direction of the arrows, and showing the parts in opened and closed positions, the latter being indicated in dotted lines.

Figure 3, is a transverse section taken on

line 3—3 of Figure 1, looking in the direction of the arrows. 55

Figure 4, is a fragmentary sectional view on line 4—4, Figure 2, showing the detailed construction of the operating switch blade and the spring clip for the fuse element. 60

Figure 5 is perspective of one of the spring contacts.

The drawings schematically illustrate a preferred or typical embodiment of my invention, and for convenience I have employed 65 similar reference characters to designate like parts wherever they appear throughout the several views.

This switch is of the enclosed type, being contained within a metal box that consists 70 of longitudinally disposed parallel side walls 5 and 6, connected at their ends by oppositely disposed end-walls 7 and 8, and the rear edges of all of said walls are connected to a rear or back wall 9. A cover or closure in the form 75 of a metal door 10 is connected by hinges 11 to the outer edges of the side wall 5 and means may be provided to lock or latch the door when closed to prevent tampering or meddling with the switch by unauthorized persons. Plates of insulation 12 and 13 are secured to the inner surfaces of the side walls 80 5 and 6 and are substantially the height thereof but slightly less in length than the respective walls, and a plate of insulation 14 85 is preferably placed against the inner surface of the back or rear wall 9 which plate is of substantially the dimensions of the adjacent wall. Thus the interior of the box is insulated at all places that are contiguous to the 90 live parts of the switch that liability of short-circuiting is prevented.

The preferred manner of operating the movable parts of the switch is by means of a rock shaft 15 that is preferably of rectangular section where it extends between the side walls of the box and its ends are reduced and are of cylindrical section as at 16 for journaling the same in the side walls 5 and 6. One end of the rock shaft passes through the side 100 walls 6 and is provided with suitable operating mechanism, which includes a swinging lever or handle 17. At points slightly spaced from the side walls 5 and 6 said rockshaft has lateral arms 18 secured to it, the outer ends of which are formed into apertured bosses 19, while their opposite ends are provided with bifurcations 20 that are positioned

upon opposite faces of the rock shaft and are secured thereto by clamping devices 21 such as bolts and nuts.

Secured upon the side walls 5 and 6 and projecting inwardly towards each other are spacers or blocks 22 that carry upon their inner ends suitable spring contacts that consist of a strip of metal bent back upon itself to provide a mounting portion 23 beyond which the metal strip is offset in opposite directions as at 24 to provide spaced flexible arms or leaves 25 as illustrated in Figure 5. There are a plurality of these spring contacts upon the side walls 5 and 6 of the box and the same are arranged in pairs upon said opposite walls, so that each contact upon wall 5 will align with a spring contact upon wall 6. Studs 26 project from blocks 22 through apertures in the spring contacts and next said contacts there are spacing washers 27 while the flattened lateral ends 28 of tubular terminals 29 are mounted on the studs 26 beyond the washers so that when the binding nuts 30 are screwed upon the studs 26 the several parts will be securely clamped in position. The structure last described constitutes the stationary element of the switch, and is preferably mounted in the lower portion of the box adjacent but spaced from the rear or back wall thereof.

Secured to and projecting inwardly from the upper portion of the side walls are bracket blocks 31 that are above the spring arms 25 of the fixed contacts. Studs 32 project inwardly from the blocks 31 to receive the folded back upper end portion 33 of movable blades 34 that pivot upon studs 32 and at their lower ends are adapted to coact with and be moved into frictional contact with and between the spring arms 25 of the respective fixed contacts. Intermediate their ends these blades 34 are operatively connected by pivots 35 to the inner faces of longitudinally reciprocable links 36, by means of which the blades or arms 34 are simultaneously operated. The links 36 are of insulating material and are connected at their ends nearest rock-shaft 15 by means of a pivot stud 37 to the apertured bosses on the outer ends of arms 18. As seen, there are preferably two of these reciprocable links 36, one mounted upon each side of the box and each link is pivotally connected to a plurality of switch blades or arms 34 that are arranged upon its respective side of the box.

As hereinbefore stated the ends of the blades 34 adjacent their pivots have the folded-back portions 33 through which the pivots pass. The ends of the portions that are folded back are bent laterally as at 38 to provide means in the form of brackets or seats to which fuse-clips 39 are suitably secured. These brackets or seats upon one side of the structure project towards and are in alignment with those upon the opposite side and the fuse clips, as seen in Figure 2, are substan-

tially U-shaped and open upwardly so that the fuses are readily accessible when the door is opened. The fuse clips are mounted at the connecting web of their U-shape formation so that the arms of the U constitute 70 spring members to receive the ends of the fuses and said arms open outwardly towards the door or cover to permit ready removal or insertion of the fuses. The fuses by this arrangement are positioned a considerable distance from the contacts and the conductors or cables so that liability of a person being injured from the latter is reduced to a minimum. By reference to Figures 1 and 3, it will be seen there is considerable space in the central portion of the box, both between the oppositely arranged elements of the switch and between the fuses and the bottom of the box, so that the cables and conductors may be readily taken care of without the confusion that is usual in switch boxes. The arrangement and disposition of the parts in the manner described permits of quick assembly in manufacture because of the fact that the parts are carried from the side walls 90 of the box. By the arrangement herein disclosed the current will flow in a somewhat circular path from a terminal contact through its blade, then through its fuse to the opposite blade and the other terminal contact, thus creating what is known as a solenoid. This sets up a strong magnetic path parallel to the switch members and causing the well-known "blow-out" effect when opening the switch under load, thereby ameliorating the 100 usual excessive burning out of the contact members.

What I claim as new is:

1. An electric switch comprising a boxlike housing and closure therefor, a plurality of switch contacts mounted upon a wall of said housing, a corresponding number of blades pivotally mounted on said wall and movable into and out of engagement with said switch contact, a corresponding plurality of similar switch contacts and blades mounted opposite the first-mentioned switch elements, a plurality of conducting elements mounted upon and bridging said oppositely disposed blades, means connecting each set of blades, and devices common to both means for operating the latter to move said blades.

2. An electric switch comprising a boxlike housing and closure therefor, a plurality of switch contacts mounted upon a wall of said housing, a corresponding number of blades pivotally mounted on said wall and movable into and out of engagement with said switch contacts, a corresponding plurality of similar switch contacts and blades mounted opposite the first-mentioned switch elements, a plurality of conducting elements mounted upon and bridging said oppositely disposed blades, a link for each set of blades that operatively connect the same, and a common rocking ele-

ment operatively connecting said links whereby to move all of the blades simultaneously.

3. An electric switch comprising a boxlike housing and closure therefor, a plurality of switch contacts mounted upon a wall of said housing, a corresponding number of blades pivotally mounted on said wall and movable into and out of engagement with said switch contact, a corresponding plurality of similar switch contacts and blades mounted opposite the first-mentioned switch elements, a plurality of clips mounted on said blades, a plurality of fusible conducting elements removably mounted in said clips and bridging said oppositely disposed blades, to provide electrical connection between the same, means connecting each set of blades, and devices common to both means for operating the latter to move said blades.
- 20 4. An electric switch comprising a boxlike housing and closure therefor, a plurality of switch contacts mounted upon a wall of said housing, a corresponding number of blades pivotally mounted on said wall and movable into and out of engagement with said switch contact, a corresponding plurality of similar switch contacts and blades mounted opposite the first-mentioned switch elements, a plurality of clips mounted on said blades, a plurality of fusible conducting elements removably mounted in opposite pairs of clips and bridging said oppositely disposed blades, a link for each set of blades that operatively connect the same, and a common rocking element operatively connecting said links whereby to move all of the blades simultaneously.

5. An electric switch comprising substantially parallel supports, a plurality of fixed contacts arranged opposite each other upon the respective supports, a plurality of movable contacts pivotally mounted upon the respective supports one adjacent and locking with a respective fixed contact, means adjacent each support operatively connecting the respective movable contacts, and fusible means electrically connecting opposite pairs of movable contacts at the pivot of the latter.

6. An electric switch comprising substantially parallel supports, a plurality of fixed contacts arranged opposite each other upon the respective supports, a plurality of movable contacts pivotally mounted upon the respective supports one adjacent and coacting with a respective fixed contact, a longitudinally reciprocable bar adjacent each support operatively connected to the respective movable contacts, means for operating said bars, and removable fusible means electrically connecting opposite pairs of movable contacts at the pivots of the latter.

7. An electric switch comprising substantially parallel supports, a plurality of fixed contacts arranged opposite each other upon the respective supports, a plurality of movable contacts pivotally mounted upon the re-

spective supports one adjacent and coacting with a respective fixed contact, a longitudinally reciprocable bar operatively connected to the respective series of movable contacts and disposed alongside and movable in planes parallel with the respective supports, means for reciprocating said bars, and removable fuses forming electrical connection between opposite movable contacts, said fuses extending between the pivots of the latter.

8. An electric switch comprising substantially parallel supports, a plurality of fixed contacts arranged opposite each other upon the respective supports, a plurality of movable contacts pivotally mounted upon the respective supports one adjacent and coacting with a respective fixed contact, a longitudinally reciprocable bar operatively connected to the respective series of movable contacts and disposed alongside and movable in planes parallel with the respective supports, a rock-shaft journaled in said supports and disposed transversely of said bars, arms extending from said shaft and operatively connected to the respective bars, and fuses removably carried by opposite movable contacts at the pivots of the latter and adapted to form electrical connection therebetween.

9. An electric switch comprising spaced stationary supporting plates arranged parallel and facing each other, a plurality of feed-contacts upon a face of one of said plates, a plurality of blades pivoted on said plate adjacent said feed-contacts, means connecting said blades, a plurality of discharge-contacts fixed on a face of the other plate, a plurality of blades pivoted on said other plate adjacent said feed-contacts, means connecting said last-mentioned blades, fuses connecting the blades on one plate with opposite blades on the other plate, and means for operating all of said blades simultaneously.

10. An electric switch comprising a housing having an open front and a closure therefor, insulating supporting plates arranged along the opposite walls of the housing between its closure and back, said plates being parallel and opposite each other, a plurality of feed-contacts fixed upon a face of one of said plates adjacent the back of the housing, a plurality of blades pivoted on said plate adjacent the closure, means connecting said blades, a plurality of discharge-contacts fixed on a face of the other plate, each contact being opposite a contact on the first-mentioned plate, a plurality of blades pivoted on said other plate adjacent the closure, means connecting said last-mentioned blades, fuses connecting the blades on one plate with opposite blades on the other plate, and means for operating all of said blades simultaneously.

11. An electric switch comprising spaced stationary supporting plates arranged parallel and facing each other, a plurality of feed-contacts fixed upon a face of one of said

- plates, a plurality of blades pivoted on said plate adjacent said feed-contacts, means connecting said blades, a plurality of discharge-contacts fixed on a face of the other plate, 5 a plurality of blades pivoted on said other plate adjacent said feed-contacts, means connecting said last mentioned blades, fuses connecting the blades on one plate with opposite blades on the other plate, said fuses being positioned at the pivots of said blades whereby to be capable of rotative movement only when said blades are operated, and means for operating all of said blades simultaneously. 10
12. An electric-switch comprising a housing having an open front and a closure therefor, insulating supporting plates arranged along the opposite side walls of the housing between its closure and back, said plates being parallel and opposite each other, a plurality of feed-contacts fixed upon a face of one of said plates adjacent the back of the housing, a plurality of blades pivoted on said plate adjacent the closure means connecting said blades, a plurality of discharge-contacts fixed on a face of the other plate, 25 each contact being opposite a contact on the first-mentioned plate, a plurality of blades pivoted on said other plate adjacent the closure, means connecting said last-mentioned blades, fuses connecting the blades on one 30 plate with opposite blades on the other plate, said fuses being positioned at the pivots of said blades whereby to be capable of rotative movement only when said blades are operated, and means for operating all of said 35 blades simultaneously.

Signed at Chicago, in the county of Cook and State of Illinois, this 9th day of March, 1927.

MARTIN P. LUTHER.
